MULTI-POINT ELECTRICAL CONTROLLER

Donald S. Michael, 394 Ackerman Ave., Glen Rock, N.J.

Filed Nov. 10, 1961, Ser. No. 67,459

Term of patent 14 years

(Cl. D26—5)

The single figure is a perspective view of a multi-point electrical controller showing my new design.

The dominant features of my new design are shown in solid lines in the drawing.

The right side is the same as the left and the back is conventionally flat and unornamented.

I claim:

The ornamental design for a multi-point electrical controller, as shown and described.
